(57) **CLAIM**

The ornamental design for a dehumidifying, deodorizing and wrinkle-reducing machine for clothing, as shown and described.

DESCRIPTION

1. Dehumidifying, deodorizing and wrinkle-reducing machine for clothing

1.1 : Right top perspective view

1.2 : Left top perspective view

1.3 : Right bottom perspective view

1.4 : Left bottom perspective view

1.5 : Front

1.6 : Reference view

1.7 : Reference view 2

The broken lines depict portions of a dehumidifying, deodorizing and wrinkle-reducing machine for clothing that form no part of the claimed design; the fine lines on the drawings indicate the flat or curved surface; reproduction 1.1 is a right top perspective view of the dehumidifying, deodorizing and wrinkle-reducing machine for clothing; reproduction 1.2 is a left top perspective view thereof; reproduction 1.3 is a right bottom perspective view thereof; reproduction 1.4 is a left bottom perspective view thereof; reproduction 1.5 is a front view thereof; reproduction 1.6 is a reference view showing a process in which the pants press at the inside left part slides out, and form no part of the claimed design; reproduction 1.7 is a reference view showing a drawer-type compartment for water tanks at the lower front part has been taken out, and form no part of the claimed design; this is a design for a dehumidifying, deodorizing and wrinkle-reducing machine for clothing with a pants press provided on the inner left side; the pants press can be slid out; at the front lower part, there is a drawer-type compartment for water tanks; at the inside upper part, there are hangers having a lighting function; for air cleaning and dehumidification, suction holes are provided on the inside bottom and top.

1 Claim, 7 Drawing Sheets
